SHIRT CUFF AND METHOD AND APPARATUS
FOR MAKING ITEarl V. Tolen and Charles B. Harbstreit, Bedford,
Ind., assignors to Reliance Manufacturing Com-
pany, Chicago, Ill., a corporation of Illinois

Application March 18, 1933, Serial No. 661,477

3 Claims. (Cl. 2—123)

Our invention relates to shirt cuffs and method and apparatus for making them. It is especially concerned with that type of cuff using two plies—an inner ply and an outer ply, whether or not an intermediate reinforcing ply is used.

One feature of our invention is a simplified construction and method where but one stitching (which may be single, double or even triple) may be formed, preferably by a continuous operation, about the perimeter of the cuff and thereby secure all plies of the cuff together and secure the cuff to the shirt sleeve, without the necessity of any other securing.

Our invention also embraces improved guide attachments for the sewing machine for effecting this method and construction.

The foregoing together with further objects, features and advantages of our invention are set forth in the following description of the specific embodiments thereof and illustrated in the accompanying drawings, wherein:

Fig. 1 is a plan view of the respective plies of a three-ply cuff as delivered by a folding machine which folds back and creases the margins of the plies;

Fig. 2 is a plan section of a sewing machine taken on a plane slightly above the table omitting the parts not directly concerned with the invention;

Fig. 3 is a view similar to Fig. 2, but showing the start of the stitching securing the plies together and to the sleeve;

Figs. 4, 5 and 6 are fragmentary views similar to Fig. 3 but showing the line of stitching as it progresses across the various sides of the cuff;

Fig. 7 is a fragmentary vertical section which may be considered as taken on the line 7—7 of Fig. 2 and showing the presser foot and needle in side elevation;

Fig. 8 is a somewhat similar vertical section taken on the line 8—8 of Fig. 3 and looking toward the needle, with part of the presser foot in cross section;

Fig. 9 is a view similar to Fig. 8 but taken on the line 9—9 of Fig. 3 forwardly of the plane of the section of Fig. 8; and

Fig. 10 is a transverse section through the completed cuff assembly.

Referring first to the finished product by reference to the transverse section thereof in Fig. 10, the cuff 15, to be sewn along the outer end of the sleeve 16, comprises the inner fabric ply 17, the outer fabric ply 18 and an intermediate reinforcing ply of stiff buckram 19. The margins 17', 18' and 19' of the several plies are folded in-

wardly to provide folded peripheral edges for the plies. Preferably these folded margins are pre-formed by a folding machine which acts upon the blanks for the three plies simultaneously, delivering them in nested relation, as shown in Fig. 5.

1. The outer ply 17 of the nested plies is pulled from the other two, the start of this being shown in Fig. 1. The inner plies 18 and the reinforcing ply 19 are left in nested relation. The nested inner ply 18 and reinforcing ply 19 are then turned 10 end for end and the outer ply 17 placed upon it with the margins aligned and with the end of the sleeve 16 extending between the sleeve ends of the folded margins 17' and 18'.

The first reach 20a of a line of stitching 20 is 15 then formed, as shown in Fig. 3, along the sleeve edge of the cuff. We have shown a single needle sewing machine, although we contemplate that a double or triple needle sewing machine can be used, depending, of course, on whether a single, 20 double or triple stitching is desired. In any case, there is but one line of stitching, that is, a single operation of the sewing machine. By guide means which will later be described, the sleeve edge 18a of the upper ply is held in alignment with the 25 sleeve edge 17a of the lower ply, and the operator guides the end edge 16a of the sleeve to maintain a substantially even overlap of the cuff relative to the sleeve.

In forming the reach 20a of the stitching, the 30 operator, if the garment is so styled, introduces the necessary puckering of the end of the sleeve relative to the cuff. When the opposite corner of the sleeve edge of the cuff is reached, the assembly is rotated clockwise through 90°, as shown in Fig. 35 4, and the stitching continued, as the reach 20b, along the adjacent ends 17b and 18b of the cuff plies until the opposite side edges 17c and 18c of the cuff ply are reached.

Then the assembly is turned through a second 40 90° from the position of Fig. 4 to the position of Fig. 5 and the stitching 20 continued as the reach 20c along the cuff edge 15c and along the ply edges 17c and 18c to the next corner.

Then the assembly is rotated through a third 45 90° from the position of Fig. 5 to that of Fig. 6, where the stitching 20 is continued as the reach 20d through the end edges 17d and 18d of the plies, the line of stitching 20 terminating substantially at the point where it began.

50 Referring now to the apparatus by which this construction and method are effected, we have omitted showing much of the sewing machine which is not directly concerned with our invention, such as the operating mechanism, the lower 55

feed dog, and the like. The needle 25 works through a hole or slot 26 (Fig. 8) in the presser foot 27 which has the usual upturned toe 28. The foot is forwardly bifurcated by a cut 29 in which is disposed a vertical guide 30 having a suitably rounded front end and a resilient supporting finger 31 attached at 32 to the presser foot or its support. Structurally, the vertical guide 30 and the finger 31 may be stamped from a single sheet 10 of spring steel bent at right angles as at 33, so that the guide 30 is primarily in a vertical plane and the finger 31 primarily in a horizontal plane.

The important functions of guide 30 are first that it forms a lateral abutment right-facing in Figs. 8 and 9, for the edge of the upper ply, and second that it be resiliently mounted so that when the presser foot comes down against the table 34 of the sewing machine, the guide may give vertically as necessary while still continuing to press downwardly. When stitching the sleeve edge 15a of the cuff, where reach 20a of the stitching includes the end of the sleeve, the lower edge of the guide 30 will ride upon the sleeve. In stitching the other three edges, 15b, 15c and 15d of the cuff, where the sleeve is not included in the stitching, the lower edge of the guide 30 contacts the table 34 directly. In the latter instance, the guide 30 forms a right facing abutment for the adjacent edge of the lower ply as well as for that of the upper ply. As an auxiliary guide for the adjacent edge of the under ply under the latter circumstance, and as a primary guide for the adjacent edge of the under ply under the former circumstance—that is, when the sleeve extends between the two ply edges when stitching the sleeve edge 15a of the cuff—we provide another guide 35, which we term a table guide as distinguished from the presser foot guide 30. The table guide may conveniently be in the form of a rectangular plate having one corner cut away to provide clearance around the presser foot and secured to the table 34 and affording at one edge a right facing abutment 35'. The plate 35 may be of relatively thin metal stock and removably secured to the table by screws so that it may be removed when work of another character is to be done on the machine. Incidentally, the presser foot guide 30 may be removed by unscrewing its retaining screw 32, in which event the presser foot will function in the usual manner for ordinary work.

The guiding abutment 35' of the guide plate 35 is disposed forwardly of the sewing needle and slightly to the side of the line of feed passing through the needle, depending upon how far in from the edge the stitching is to come. The guide face 35' is also in alignment with the guiding face of the presser foot guide 30. By holding both the upper and lower ply of the collar band with their edges being sewn in contact with the respective guides 30 and 35, the operator is enabled to keep the edges in alignment—that is, without one protruding laterally beyond the other—whether or not the side is one where the sleeve extends out from between the plies.

By our invention, the plies of the cuff at the sleeve edge 15a are simultaneously secured together and to the end of the sleeve by the one reach of stitching 20a, and this is the only securing there is or need be either to hold the plies of the cuff together at that edge or to hold any part of the cuff to the end of the sleeve. This eliminates the customary operation of first sewing one ply of the cuff to the end of the sleeve with the ply and the sleeve end one above the

other and on the same side of the needle, and after that preliminary stitching, reversing the seam thus formed and running a second stitching across the edge to secure the other ply to the sleeve and to the first ply.

Because the guides 30 and 35 align the sleeve edges 17a and 18a of the respective plies, and as the folding machine delivers the two plies quite accurately of the same width, it follows that after the first reach of stitching 20a has been 10 formed by our apparatus, the opposite edges 17c and 18c of the respective plies are also aligned without one protruding beyond the other. For this reason we are able successfully to sew the outer edge 15c of the cuff after we sew the sleeve 15 edge. In fact, we are enabled to sew together the sleeve edges of the plies of the cuff and also sew them to the sleeve in a single reach of a sole and initial stitching operation, and thereafter to continue the line of stitching successively 20 along each of the other three edges.

Having thus described our invention, what we claim is:

1. The method of attaching a two ply cuff to the end of a sleeve having greater initial width 25 than the length of the cuff, which consists in pre-forming inturned marginal flanges on an inner and an outer ply, guiding the sleeve margins of the respective cuff plies in alignment, with their adjacent margins facing, and with the end of the 30 sleeve extending therebetween and, while the sleeve is otherwise unattached to either ply along the end of the sleeve, forming a line of stitching along the sleeve edge of the cuff and passing through the outer ply, its inturned inner margin, 35 the end of the sleeve, the inturned margin of the inner ply, and the inner ply, with the stitching exposed on both faces of the cuff, and gathering the sleeve as the line of stitching is formed to bring the edges of the sleeve into alignment with 40 the ends of the cuff, and thereafter, while the plies are unattached to the sleeve save for the first-mentioned stitching, and as a continuation of the same stitching, stitching one end, then the opposite edge and then the other end of the 45 plies together by stitching extending through the outer ply, its inturned margin, the inturned margin of the inner ply, and the inner ply, with the last mentioned stitching exposed on both faces of the cuff, and said stitching constituting the 50 sole sewn securing of the plies to each other and to the sleeve.

2. The method of attaching a two ply cuff to the end of a sleeve having greater initial width than the length of the cuff, which consists in 55 pre-forming inturned marginal flanges on an inner and an outer ply, guiding the sleeve margins of the respective cuff plies in alignment, with their adjacent margins facing, and with the end of the sleeve extending therebetween and, while the 60 sleeve is otherwise unattached to either ply along the end of the sleeve, forming a line of stitching along the sleeve edge of the cuff and passing through the outer ply, its inturned inner margin, the end of the sleeve, the inturned margin of the 65 inner ply, and the inner ply, with the stitching exposed on both faces of the cuff, and gathering the sleeve as the line of stitching is formed to bring the edges of the sleeve into alignment with the ends of the cuff.

3. The method of attaching a two ply cuff to the end of a sleeve having greater initial width than the length of the cuff, which consists in 70 pre-forming inturned marginal flanges on an inner and an outer ply, superposing the plies with 75

their inturned flanges facing, and securing the plies together by a continuous line of stitching run along the several sides of the cuff serially and extending through the outer ply, its inturned 5 margin, the inturned margin of the inner ply, and the inner ply, with the last mentioned stitching exposed on both faces of the cuff, and said stitching constituting the sole sewn securement of the plies to each other and to the sleeve, said 10 stitching operation, as performed along the sleeve edge of the cuff, consisting of guiding the sleeve margins of the respective cuff plies in alignment, with their adjacent margins facing, and with the

end of the sleeve extending therebetween and, while the sleeve is otherwise unattached to either ply along the end of the sleeve, forming a line of stitching along the sleeve edge of the cuff and passing through the outer ply, its inturned inner 5 margin, the end of the sleeve, the inturned margin of the inner ply, and the inner ply, with the stitching exposed on both faces of the cuff, and gathering the sleeve as the line of stitching is formed to bring the edges of the sleeve into alignment with the ends of the cuff. 10
